UNITED STATES PATENT OFFICE.

CHARLES H. BEELER, JR., OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 20,700, dated April 28, 1891.

Application filed February 6, 1891. Serial No. 380,503. Term of patent 7 years.

To all whom it may concern:

Be it known that I, CHARLES H. BEELER, Jr., a citizen of the United States, and a resident of Philadelphia, Pennsylvania, have invented
5 a Design for a Font of Type, of which the following is a specification.

My design for a font of type is clearly illustrated in the accompanying typographical impression.
10 The general character of the design is that of a shaded letter, the special feature of the design being the square shape of the majority of the letters, the faces of the letters being solid and having shading-lines on the right side and on the under side.
15

The sharp corners of the letters A, E, F, H, I, K, L, M, N, P, B, W, X, Y, and Z are curved outward to a point or fin, while the corners of

the letters C, G, O, Q, and S are rounded. The right-hand corners of the letters B, D, P, 20 and R are slightly rounded, while the left-hand corners are pointed. The lower portion of the letter U is slightly rounded. The numerals are in keeping with the letters of the font.

I claim—

The design for a font of type, substantially as herein described, and as shown in the accompanying typographical impression.

In testimony whereof I have signed my 30 name to this specification in the presence of two subscribing witnesses.

CHARLES H. BEELER, JR.
